UNITED STATES PATENT OFFICE.

FRANK DONAS, OF MONTREAL, QUEBEC, CANADA.

DESIGN FOR A WEAPON.

47,748.

Specification for Design. Patented Aug. 24, 1915.

Application filed May 10, 1915. Serial No. 27,288. Term of patent 7 years.

To all whom it may concern:

Be it known that I, FRANK DONAS, a subject of the Emperor of Austria-Hungary, and residing at Montreal, Quebec, Canada, have invented a new, original, and ornamental Design for a Weapon, of which the following is a specification, reference being had to the accompanying drawing, forming part thereof.

The figure is a view in side elevation of a weapon, showing my new design.

I claim:

The ornamental design for a weapon, as shown.

FRANK DONAS.

Witnesses:

FRANK VERTYNSKI,
LUDWIK VIERCYNISKI.
